UNITED STATES PATENT OFFICE.

KARL BAUMANN, OF URMSTON, ENGLAND, ASSIGNOR, BY MESNE ASSIGNMENTS, TO
WESTINGHOUSE GEAR AND DYNAMOMETER COMPANY, A CORPORATION OF PENN-
SYLVANIA.

REDUCTION GEARING.

Application filed June 22, 1923, Serial No. 647,121, and in Great Britain July 25, 1922.

This invention relates to floating frames for use in connection with power transmission gearing.

In gearing of the floating frame type it has been customary to make the floating frames substantially symmetrical with respect to the center line of the bearings, that is to say, with the top and bottom halves of the frame of practically the same shape and size. This construction was adopted partly to obtain the requisite strength but mainly to prevent distortion of the frame in the event of the bearings and the parts of the frame adjacent thereto becoming heated to a greater extent than the remainder of the frame. With this arrangement however the bearings are inaccessible owing to the halves of the frame being secured together by fitting bolts in order to attain the requisite strength and prevent sliding of one surface relative to the other at the horizontal joint.

In accordance with the present invention the floating frame is disposed mainly at one side of the center line of the bearings and means are provided for maintaining a substantially uniform temperature throughout the frame so as to prevent distortion due to unequal expansion or contraction, or for indicating difference in temperature between different parts of the frame or for indicating any distortion of the frame so that in either case the gear can be thrown out of operation and the cause of such indication investigated and removed. In some cases, as a precautionary measure, a plurality of such means may be provided in connection with a single frame. For instance, one or other of the indicating devices may be provided in addition to the temperature equalizing means so that in the event of the failure of the latter and a difference in temperature in excess of a predetermined amount arising between different parts of the frame, or of excessive overheating of any part of the frame rendering such means ineffective, the difference in temperature or any distortion due thereto will operate to energize the indicating device. The means for maintaining a substantially uniform temperature throughout the frame may take the form of heat insulating means between the bearings and the frame or of a special construction of frame permitting the circulation of a cooling or heating medium therethrough, or of a combination of these arrangements; the

means operating by reason of a difference in temperature may consist of thermal couples at or near the bearings and at another part of the frame, the difference between the electromotive forces of which couples causes a current to flow through and actuate an alarm device or an indicator when the temperature difference exceeds a predetermined amount; and the means for indicating any distortion of the frame may consist of any suitable or known device for indicating inequalities of expansion or contraction.

In order that the invention may be more clearly understood and readily carried into practice reference will now be made to the accompanying drawings which illustrate by way of example several forms of floating frame constructed in accordance therewith; Fig. 1 being a side elevation of one form; Fig. 2 a section on the line II—II of Fig. 1; Fig. 3 a view similar to Fig. 2 illustrating a slight modification; Figs. 4, 6 and 8 longitudinal sections through other forms of frames, and Figs. 5, 7 and 9 transverse sections on the lines V—V, VII—VII and IX—IX, respectively of Figs. 4, 6 and 8.

In each form illustrated the frame 10 is of substantially semi-circular formation having side brackets 11 formed integral therewith and bearings 12 mounted on the diametral portion thereof, the brackets 11 being mounted, when the gear is assembled, on flexible I-beams 13 or their equivalent secured to seatings on the gear case and the bearings 12 carrying under similar circumstances a high speed or intermediate shaft of the gearing.

In the forms illustrated by Figs. 1 to 3 the bearings 12 are insulated from the frames 10 by heat insulating liners 14 and by channels 15 formed between the underside of the bearings and the frames. In the form illustrated by Figs. 1 and 2 these channels are open at the ends and adapted to admit of the circulation of air around the part of the bearings adjacent the frame 10 and in the form illustrated by Fig. 3 they are closed at the ends and provided with oil inlet and outlet ports 16 and 17 respectively so that cool lubricating oil may be passed therethrough on its way to the bearings.

In the forms illustrated by Figs. 4 to 7 the bottom half of the housing of the bearing 12 is formed integral with the frame 10 and in the form illustrated by Figs. 4 and 5 a

peripheral passage 18 is formed completely around the frame with a partition 19 beneath the central bearing 12 while in the form illustrated by Figs. 6 and 7 the whole frame 10 is hollow and has internal baffles 20 projecting alternately from the top and bottom thereof. In each case ports 21 are provided at opposite ends of the channel formed in the frame so that cooling medium, which may conveniently be lubricating oil for the bearings 12, can be circulated therethrough to maintain a substantially uniform temperature throughout the frame. In the form illustrated by Figs. 4 and 5 the channel 18 may be so arranged that the walls thereof increase the rigidity of the frame in a manner similar to that described in the specification of the prior British Letters Patent No. 149,329.

In the form illustrated by Figs. 8 and 9 the bearings 12 are insulated from the frame 10 by channels 15 through which air may circulate as in the form illustrated by Figs. 1 and 2 and radiating ribs or fins 22 are provided on the parts of the frame adjacent the bearings to dissipate any heat transmitted thereto from the bearings into the atmosphere. Ribs 23 (indicated in dotted lines in Fig. 8 only) may also be provided to conduct into and distribute substantially uniformly throughout the frame any heat remaining in the bearings or in the parts of the frame adjacent thereto.

In any form of the invention where the bearings 12 are formed independently of the frame 10 they may be insulated from the latter by being connected therewith through a number of point supports, thereby dispensing with the necessity for interposing heat insulating liners, such as 14 in Figs. 1 to 3, between the frame and the bearings.

A plurality of the aforesaid arrangements for maintaining a substantially uniform temperature throughout the frame may, where it is both practicable and desirable, be embodied in a single construction and in any form or arrangement a thermostat or a thermal couple working in conjunction with an indicating or alarm device, as for instance the electric circuit with thermal couple and alarm device indicated diagrammatically at 24 in Fig. 1 of the drawings, or a device for measuring differences of expansion may be provided to cause an

audible or visual indication to be given in the event of the failure of the temperature equalizing means and a difference of temperature in excess of a predetermined amount arising between different parts of the frame, or in the event of excessive over-heating of any part of the frame rendering such means ineffective, or in the event of any distortion taking place in the frame.

Having now particularly described and ascertained the nature of my said invention and in what manner the same is to be performed, I declare that what I claim is:

1. In or for power transmission gearing a floating frame structure comprising a frame and one or more bearings wherein the floating frame is disposed mainly at one side of the center line of the bearing or bearings and means are provided for maintaining a substantially uniform temperature throughout the frame.

2. In or for power transmission gearing, a floating frame structure comprising a frame and one or more bearings wherein the frame is disposed mainly at one side of and is insulated from the bearing or bearings.

3. In or for power transmission gearing, a floating frame structure comprising a frame and one or more bearings wherein the frame is disposed mainly at one side of the bearing or bearings and provision is made in the frame for the passage of heat conducting medium therethrough.

4. A floating frame structure as claimed in claim 2, wherein the part of the frame adjacent the bearing or bearings is provided with means for dissipating into the surrounding atmosphere any heat transmitted thereto from said bearing or bearings.

5. A floating frame structure as claimed in claim 2, wherein the part of the frame adjacent the bearing or bearings is provided with means for dissipating into the surrounding atmosphere any heat transmitted thereto from said bearing or bearings, and wherein means are also provided to conduct into and to substantially equally distribute throughout the frame, heat from the bearing or bearings or from the part of the frame adjacent thereto.

In testimony whereof, I have hereunto subscribed my name this fifth day of June, 1923.

KARL BAUMANN.
